US00D957682S

(12) **United States Design Patent** (10) **Patent No.:** **US D957,682 S**
(45) **Date of Patent:** **** Jul. 12, 2022**

(54) **PIPETTE TIP RECEPTACLE PLATE**

(71) Applicant: **BIOTIX, INC.**, San Diego, CA (US)

(72) Inventors: **Juan Martin Mendez Padilla**, Tijuana (MX); **Arta Motadel**, San Diego, CA (US); **Peter Paul Blaszczak**, San Diego, CA (US)

(73) Assignee: **BIOTIX, INC.**, San Diego, CA (US)

(***) Term: **15 Years**

(21) Appl. No.: **29/759,427**

(22) Filed: **Nov. 23, 2020**

Related U.S. Application Data

(62) Division of application No. 29/692,493, filed on May 24, 2019, now Pat. No. Des. 906,538, which is a division of application No. 29/592,990, filed on Feb. 3, 2017, now Pat. No. Des. 854,185.

(57) **CLAIM**

The ornamental design for a pipette tip receptacle plate, as shown and described.

DESCRIPTION

FIG. 1 is a top perspective view of a pipette tip receptacle plate;

FIG. 2 is a bottom perspective view of the plate shown in FIG. 1;

FIG. 3 is a top view of the plate shown in FIG. 1;

FIG. 4 is a bottom view of the plate shown in FIG. 1;

FIG. 5 is a longer side view of the plate shown in FIG. 1; and,

FIG. 6 is a shorter side view of the plate shown in FIG. 1.

1 Claim, 4 Drawing Sheets
